UNITED STATES PATENT OFFICE

EARLE R. FAIREY, OF HAMILTON, ONTARIO, CANADA

CALENDAR

Application filed July 15, 1929. Serial No. 378,313.

This invention relates to portable calendars and has special reference to a small portable calendar adapted to be worn on the person or carried in the pocket after the manner of a watch, a postage stamp case, a cigar lighter or the like.

The present invention relates particularly to the mechanism for operating the calendar and it is to be understood that such mechanism may be incorporated in any of the small articles ordinarily carried by a person, the calendar case forming, as may be desired, part of a compact, match case, stamp case, cigar lighter or any other like article.

One important object of the invention is to provide a simple and efficient construction of operating means for such a calendar.

A second important object of the invention is to provide means whereby a renewable annual calendar strip may be used in connection with the invention.

A third important object of the invention is to provide means whereby the strip may be suitably wound onto one roller and off of the other as desired.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a face view of the improved calendar.

Figure 2 is a detail section therethrough taken parallel to the face and showing the interior of said calendar.

Figure 3 is a section on the line 3—3 of Figure 2.

Figure 4 is a section on the line 4—4 of Figure 2.

Figure 5 is a view of one end of the calendar strip.

Figure 6 is a view of the other end thereof.

In the present embodiment of the invention there is provided a casing 10 having an opening in its front covered by a lens or

crystal 11 and at each end of this casing is a winding roller 12 slotted as at 13 to receive the tapered ends 14 of a calendar strip 15 having a series of monthly calendars printed thereon. Close beneath the lens or crystal is a guide plate 16 and the calendar strip runs from one roller over the guide plate and down to the other roller. Each of the rollers 12 carries a gear 17 and at right angles to and meshing with this gear is a gear 18. It is to be understood that these gears are the ordinary watch work type so that, while at right angles, they do not have to be beveled gears. Extending through one side of the casing is a winding pin 19 having on its outer end a winding knob 20 and on its inner end a gear 21 which meshes with a gear 22 mounted at right angles to the gear 21 and lying in the same plane as the gears 18. A spring 23 normally holds the gear 21 out of engagement with the gear 22 but by pulling out on the knob 20 the gear 21 is brought into engagement with the gear 22 so that rotation of the knob rotates the gear 22. Idler gears 24 connect the gears 18 and the gear 22. By this means the winding shafts 12 may be rotated by the winding knob 20 in one direction or the other and the calendar strip moved to expose the desired month.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In a portable calendar, a casing, a pair of winding shafts revolubly mounted at opposite ends of said casing, gears each on a respective shaft, other gears journaled to lie close to one face of the shaft at right angles to and meshing with the respective first gears, a driving gear, a winding stem carrying said driving gear, a knob in said stem, and idler

gears connecting the driving gear and second mentioned gears.

2. In a portable calendar, a casing, a pair of winding shafts revolvably mounted at opposite ends of said casing, gears each on a respective shaft, other gears journaled to lie close to one face of the shaft at right angles to and meshing with the respective first gears, a driving gear, a winding stem carrying said driving gear, a knob in said stem, idler gears connecting the driving gear and second mentioned gears and revolving in the same plane as the second mentioned gears, said driving gear being at right angles to and movable into and out of mesh with one of said idler gears, said stem being slidable in the casing to permit said movement, and a spring normally holding the driving gear out of engagement with the said idler gear.

20 3. In a portable calendar, a casing, a pair of winding shafts revolvably mounted at opposite ends of said casing, gears each on a respective shaft, other gears journaled to lie close to one face of the shaft at right angles to and meshing with the respective first gears, a driving gear, a winding stem carrying said driving gear, a knob in said stem, idler gears connecting the driving gear and second mentioned gears, said shafts each having a longitudinal slot therein, and a calendar tape having calendar indicia thereon and provided with tapered ends engaged in said slots.

4. In a portable calendar, a casing, a pair of winding shafts revolvably mounted at opposite ends of said casing, gears each on a respective shaft, other gears journaled to lie close to one face of the shaft at right angles to and meshing with the respective first gears, a driving gear, a winding stem carrying said driving gear, a knob in said stem, idler gears connecting the driving gear and second mentioned gears and revolving in the same plane as the second mentioned gears, said driving gear being at right angles to and movable into and out of mesh with one of said idler gears, said stem being slidable in the casing to permit said movement, a spring normally holding the driving gear out of engagement with the said idler gear, said shafts each having a longitudinal slot therein, and a calendar tape having calendar indicia thereon and provided with tapered ends engaged in said slots.

In testimony whereof he has affixed his signature.

55 EARLE R. FAIREY.
